UNITED STATES PATENT OFFICE.

EDWIN T. GREENFIELD, OF KIAMESHA, NEW YORK, ASSIGNOR TO GREENFIELD PAPER BOTTLE COMPANY, OF NEW YORK, N. Y., A CORPORATION OF NEW JERSEY.

ART OF MANUFACTURING PAPER BOTTLES OR CONTAINING VESSELS.

1,016,327.

Specification of Letters Patent.

Patented Feb. 6, 1912.

Application filed December 14, 1908. Serial No. 467,372.

To all whom it may concern:

Be it known that I, EDWIN T. GREENFIELD, a citizen of the United States, and resident of Kiamesha, in the county of Sullivan and State of New York, have made a new and useful Invention in the Art of Manufacturing Paper Bottles or Containing Vessels, of which the following is a specification.

My invention is directed to a novel method of manufacturing or constructing bottles or containing vessels for liquids generally, but particularly for dairy products, as milk, cream, etc., and it has for its object, to construct such a bottle or containing vessel from fibrous material, such as paper, and in such manner as to produce a bottle of great strength, minimum lightness and at a minimum cost.

My invention contemplates especially the manufacture of a bottle as disclosed in United States Patent No. 940,810, granted to me Nov. 16th, 1909, which bottle is made from a tube of paper and is of such a nature that the throat and neck of the article possess great strength thereby adapting it to be handled when being filled or transported from place to place, as ordinary glass bottles are handled, without damage or injury thereto.

In the before-mentioned patent I have illustrated and described a bottle having the body portion of tubular form and a throat decreasing in diameter from the shoulder thereof to the neck which is of cylindrical form, said throat and neck being provided with ribs in the nature of tapering box plaits giving thereto greater strength as the plaits approach the neck and mouth of the bottle proper, said bottle being also provided with a cup bottom and a mouth ring of like material, which parts are secured respectively to the bottom of the body and the mouth of the bottle proper by a concentric bead, so that the entire bottle when completed resembles very closely existing types of glass bottles as to conformation or shape and possesses the qualification of being equally strong at the parts by which it is handled during the process of filling and in transportation.

In the present application I have disclosed mechanism for constructing this bottle and I will now describe the method of making it, through the agency of such mechanism,

reference being had to the accompanying drawings, in which,

Figure 1 is a part sectional, part side elevational view of a complete mold for constructing the before-mentioned bottle, illustrating also the paper tube in position preparatory to performing the method of shaping the throat and neck of the bottle proper. Fig. 2 is a plan view as seen looking at Fig. 1 from the top toward the bottom of the drawings, upon the assumption that the throat and neck forming parts have been forced into the position shown in dotted lines Fig. 1, the clamping ring shown in this figure not being seen in Fig. 1. Fig. 3 is a vertical sectional view taken through Fig. 2 on the line X—X, the two positions of the clamping ring and clamping wedges for use therewith being shown respectively in full lines and dotted lines. Fig. 4 is a perspective view of the double or duplex forming arms which successively effect the formation of the throat and neck proper of the bottle, and then the turning down of the folds of the surplus material so as to form ribs or plaits which give increased strength to those parts. Fig. 5 is a plan view of the beading tool for securing the bottom of the bottle proper to the interior of the bottom part thereof, a similar tool of smaller dimensions being provided, for performing the like function with relation to the mouth ring at the upper end of the neck of the bottle; a sectional view of the body of the bottle being shown in position while the action of securing the bottom thereto is being effected. Fig. 6 is a sectional view taken through Fig. 5 and as seen looking therewith from the bottom toward the top of the drawings in the direction of the arrows, but upon the assumption that the operating beading lever is removed to its outer or inoperative position; this view illustrating also the bottom of the bottle proper and the manner in which it is secured to the body thereof, together with the means for detachably securing it to a bench or table. Fig. 7 is a sectional view of the neck and mouth of the completed bottle, illustrating the manner in which the mouth ring is secured to the neck proper by a beading tool like that shown in Figs. 5 and 6.

Referring now to the drawings in detail and first to Figs. 1 to 4 inclusive, 1, 2 and 3

represent respectively the body part, the throat part and the neck part of an interior forming mold having the conformation or shape of the interior of the bottle to be constructed, said mold being two part in effect; that is to say, split in the direction of its length to a point approximating the neck thereof so that the same may be spread at its bottom. 4 represents a tube made of paper or other fibrous material and having substantially the interior diameter of the exterior of the body part 1 of the mold. 5 represents the base or supporting part of the mold and 6 a wedge adapted to spread the bottom of the body part 1 thereof. 7, 7, represent a plurality of forming arms which are provided at their bottoms with dowel pins 8, 8, adapted to fit loosely in radially disposed holes in the base 5, there being two 20 of these dowel pins and corresponding holes for each arm. These arms are curvilinear in cross section at the various parts of the length thereof to conform to the exterior curvilinear surface of the completed bottle. 25 9, 9, are curvilinear parts secured to the forming arms 7, 7, by screws, as shown and the structural arrangement of all of these interconnected parts is such that when in closed position about the mold 1, 2 and 3, 30 they fit snugly against the faces of all of the parts thereof, as will be apparent on inspection of Figs. 1 and 2. 10, 10 constitute similar curvilinear forming arms designed to complete the folding down of the ribs or box plait after the first-named arms 7, 7 and the curvilinear parts 9, 9 have been drawn forward in the manner shown in Fig. 2. 11, 11 are pins pivotally securing the arms 10, 10 to the arms 7, 7, each pair of 35 arms 7, 10, thus constituting in effect one set of duplex forming arms. 12 is a clamping ring designed to apply the proper pressure to the upper ends of the arms 7, 7, during the first step of the method of the conformation of the bottle proper, and 13, 13 are wedges designed to complete the final step of the forming method by forcing the curvilinear forming arms 10, 10 into their ultimate position, as will be described in connection with the mode of operation.

Referring now to Figs. 5 and 6, I will describe the apparatus for completing the bottle by securing the cup like bottom to the bottom of the body part of the bottle, and 55 also for securing the mouth ring to the upper end of the neck. 16 represents the base of a beading tool which is constructed of steel, iron or other metal, and 17, 17 are holes therethrough for detachably securing this tool to a bench or table through the agency of pins 18, 18, 18. 19 represents a curvilinear bead forming part with a groove 20 in its exterior cylindrical surface, said bead forming part having the curvature on 60 its exterior face of the inner surface of the

tube from which the bottle is to be constructed. 21 represents the male part of the bead forming tool having the same interior curvature as the groove 20 and secured directly to an operating lever 22, pivoted at 70 one end to the base 16 and provided with an operating handle 23 at the other end thereof. 24 represents a tubular cup which is constructed by forming the same in a heated die in a well known manner to those skilled in the art of forming boxes and like articles from paper under pressure in heated dies, said cup having the same exterior diameter as the inner diameter of the tube 4. 25 (see Fig. 7) represents the neck of the completed bottle as formed in the molds above described, and 26 the mouth ring which is constructed by heated dies, in the same manner as was the cup 24, and is of such a nature that it may be slipped directly over the end 80 of the neck so as to be secured thereto by a concentric bead 27.

Having described the bottle proper and also the apparatus by which said bottle is constructed, I will now proceed to describe 90 the method of operation of forming the same.

Referring first to Figs. 1 to 4 inclusive, all of the parts of the mold proper, which are seen in Figs. 1 and 4, are first subjected 95 to heat in a furnace to such an extent as will not burn the paper when the mold is being used. The interior mold is then inserted within the tube 4 until the bottom thereof is flush with the lower end of said tube. The wedge 6 is then inserted in the bottom of the interior mold and the parts as thus interconnected are dropped into the cylindrical opening in the bottom of the base or support 5, so that when the wedge 6 which now 100 rests upon the bench or table is forced forward to its limit, the tube will be firmly secured between the mold and the inner wall of said base. In this position the four arms 7, 7, 7, 7, and curvilinear parts 9, 9, 9, 9 are 105 forced forward by the clamping ring 12, as will be apparent on inspection of Fig. 2, the ring 12 being driven down to its lowest position as seen in dotted lines Fig. 3. The parts are allowed to stand for an instant in 110 this position until the paper sets between the parts 9, 9, 9 and the interior mold.

The operation so far described performs the first step of my novel method hereinafter claimed, in that it molds or forms that 115 part of the tube lying respectively under the curvilinear parts 9, 9, 9, against the throat and neck parts of the interior forming mold, giving to the major portion of this end of the paper tube the exact conformation or 120 shape of well known types of bottles having cone-shaped throats and cylindrical necks. At the same time, however, it will be noted on examination of Fig. 2, there is a surplus 125 of the paper which is squeezed out between 130

the lateral edges of the curvilinear parts 9, 9 into the corresponding spaces between the pivoted arms 7, 7, 7. This surplus of material is in the nature of a plurality of folds, four such being shown. The ring 12 is now removed and the arms 7, 7, released so that the lateral edges of the curvilinear parts 9, 9, are released from behind the curved extensions of the paper seen in Fig. 2. The wedge 6 is now temporarily released so as to permit the bottle as thus far formed and its supporting mold to be rotated a fractional part of a revolution so as to bring the exterior curvilinear portions of the folds of the surplus material which are to constitute the plaits directly opposite the curvilinear parts 9, 9, 9, and the parts are again forced forward through the agency of the clamping ring 12 to their extreme limit, after which the arms 10, 10 are also forced forward to their extreme limit through the agency of the wedges 13, 13, and the parts as thus held are allowed to stand until all of the paper is set and the plaits have been sealed down, so to speak, against the faces of the throat and neck, said plaits being in effect of triangular form. This part of the operation constitutes a further step in the process, in that it forms a plurality of box plaits with overlapping edges, which edges are parallel with each other throughout the entire length of the neck, and the continuation of such edges converge from the lower end of the neck to the lower end of the throat or the upper end of the body portion of the bottle proper. The ring 12 and wedges 13 are now removed and the wedge 6 withdrawn from the bottom of the interior mold when the body part thereof and neck 40 of the bottle is in completed condition and ready for receiving the cup bottom and mouth ring to be applied thereto through the agency of the tool illustrated in Figs. 5 and 6, which operation will now be described. The tool illustrated in these figures of the drawings is first heated to approximately the same temperature as was the entire mold shown in Fig. 1 and it is detachably secured to a bench or table through the agency of the pins 18, 18, extending through the holes 17, 17, 17 in the base thereof. The cup 24 is now inserted in the interior of the bottom of the bottle as thus far formed with the bottom part up, and with the inner side 55 thereof resting against the curvilinear part 19 of the tool, with the bottom proper of the bottle resting firmly on the top surface of the base 16. The operator then taking hold of the handle 23 of the lever 22 advances the heated male part 21 against the bottom of the bottle with sufficient force to form the concentric bead, clearly illustrated in Fig. 6. The male part is then withdrawn and this operation repeated in sequence until a complete bead is formed around the bottom

thereof which effectually unites the same to the lower part of the body proper. This part of the operation constitutes a further step in the completion of the bottle in the sealing or securing of the bottom thereto. 70 The mouth ring 26 is now slipped over the neck of the bottle in the manner shown in Fig. 7 and a concentric bead 27 is formed therearound in the same manner as the like bead was formed around the bottom and 75 with a like tool of smaller dimensions. This operation just described constitutes the final step of the formation or shaping of the bottle and as thus formed it is subjected to a bath of molten paraffin or an equivalent waterproofing agent, which effectually seals all of the parts together and renders the body and throat parts thereof practically transparent. 80 In the practice of the method hereinbefore described of manufacturing bottles from fibrous material, such as paper, various types of apparatus may be used in effecting such method; or the same may be done by hand by first moistening all of that part of the tube above the shoulder of the body part 85 1, and forming the plaits or ribs by manipulating the same by hand, after which the folds of the surplus material which is to form said plaits may be ironed down with a heated iron and this entire portion of the 90 bottle as thus constructed subjected to a sufficient drying influence to cause it to maintain its shape or form.

While I have described the application of heat as one of the steps which constitute the method by which my novel bottle or containing vessel is formed, I do not limit myself to the use of heat in forming the completed bottle, although such agent is preferably used. Nor do I limit myself to 100 the securing of the cup 24 within the bottom of the body part, or the mouth ring 26 to the neck of the bottle, as various means of effecting this result might be devised, the essential feature of novelty in my invention 105 lying in the method of operation by which a bottle is formed from a paper or analogous fibrous tube by compression in such manner as to form strengthening ribs or plaits between the shoulder of the bottle proper and 110 the mouth thereof, and also in securing to the opposite ends of a tube of ordinary bottle conformation as thus prepared a bottom and a neck ring, which ring shall constitute the equivalent of the usual neck ring found in 115 glass or other bottles, my invention being generic to a method of operation in the manner described.

Having thus described my invention what I claim and desire to secure by Letters Patent of the United States is—

1. The described method of forming a bottle, consisting in first constructing a tube of a sheet of paper, then subjecting one end of such tube to pressure against the throat 130

- and neck parts of a bottle-shaped forming mold so as to give to the same a throat and neck conformation of like form, with a plurality of folds of surplus material located 5 radially therearound; then folding the surplus material into plaits extending in the direction of the length of the mold by the application of further pressure; then securing a cup-shaped bottom to the lower or 10 open end of the body part by indenting a concentric bead between the two parts through the agency of pressure, and finally securing a strengthening ring to the outer end of the neck in the same manner.
- 15 2. The described method of forming a bottle from paper or like pliable material, consisting in (1) constructing a tube from a sheet thereof; (2) subjecting one end of such tube to compression about one end of 20 a forming mold having a throat and neck until the paper partakes of the shape of the mold and the surplus material is formed into folds radially disposed therearound; (3) forming or shaping said folds into box- 25 plaits by pressure which plaits overlap the throat and neck as first formed and lie in the direction of the length thereof; (4) securing a bottom of cup form or shape to the bottom of the tube by indenting a concentric 30 bead between the two parts through the agency of pressure; and (5) securing a double or duplex strengthening ring to the outer end of the neck with its inner and outer walls located respectively within the 35 inner surface of the neck and around the outer surface thereof.
3. The described method of forming a bottle, consisting in first constructing a tube of a sheet of paper, then subjecting one end 40 of such tube to heat and pressure against the throat and neck parts of a bottle-shaped forming mold so as to give to the same a
- throat and neck conformation of like form, with a plurality of folds of surplus material located radially therearound; then folding the surplus material into plaits extending 45 in the direction of the length of the mold by the application of further heat and pressure; then securing a cup-shaped bottom to the lower or open end of the body part by indenting a concentric bead between the two parts through the agency of heat and pressure, and finally securing a strengthening ring to the outer end of the neck in the 50 same manner.
4. The described method of forming a bottle from paper or like pliable material, consisting in (1) constructing a tube from a sheet thereof; (2) subjecting one end of such tube to compression and heat about one end of a forming mold having a throat and neck until the paper partakes of the shape of the mold and the surplus material is formed into folds radially disposed therearound; (3) forming or shaping said folds 55 into box-plaits by heat and pressure, which plaits overlap the throat and neck as first formed and lie in the direction of the length thereof; (4) securing a bottom of cup form or shape to the bottom of the tube by indenting a concentric bead between the two parts through the agency of heat and pressure; and (5) securing a double or duplex 60 strengthening ring to the outer end of the neck with its inner and outer walls located respectively within the inner surface of the neck and around the outer surface thereof.
- In testimony whereof I have signed my name to this specification in the presence of two subscribing witnesses.
